KITCHEN SLICING KNIFE

Joseph Marx, Woodside, N. Y.

Application April 18, 1955, Serial No. 35,553

Term of patent 14 years

(Cl. D22—3)

FIG. 1.

FIG. 2.

FIG. 3.

Fig. 1 is a side elevation of a kitchen slicing knife, showing my new design;

Fig. 2 is a top edge elevation thereof;

Fig. 3 is a section taken on the line 3—3 of Fig. 1 and looking in the direction of the arrows; and

I claim:

The ornamental design for a kitchen slicing knife, as shown.
